(57) **CLAIM**

The ornamental design of a suction nozzle hood for a floor care appliance, as shown and described.

DESCRIPTION

FIG. 1 is a front perspective view of a suction nozzle hood of a floor care appliance showing our new design;

FIG. 2 is a front view thereof;

FIG. 3 is a left side view thereof;

FIG. 4 is a right side view thereof; and,

FIG. 5 is a top view thereof.

The portions shown in dashed lines are shown for illustrative purposes only and form no part of the claimed design.
